Attorneys.

UNITED STATES PATENT OFFICE.

BENJAMIN W. KERR, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

INSULATOR CAP.

Application filed March 13, 1922. Serial No. 543,395.

This invention relates to electric insulators and more particularly to means for attaching or securing a structure to be insulated by the insulator.

5 It is the more special object of the invention to provide an insulator with means for facilitating the attachment thereto of a structure to be supported thereby.

For a full understanding reference is made 10 to the accompanying drawings in which

Fig. 1 is a side elevation of an insulator embodying the invention;

Fig. 2 is a plan view of the principal part 15 of the invention;

Fig. 3 is a section on line 3—3 Fig. 2; and Fig. 4 is a fragmentary view in side elevation of a part shown in Fig. 2.

In Fig. 1, 10 represents an insulator having a forged steel pin 11, a plurality of 20 petticoats 12, the upper one of which has a top portion 13 provided with the usual groove 14 for carrying a conductor.

The insulator thus described may be of 25 any standard or preferred type.

According to the invention a cap 15 30 formed of pressed steel is attached to the top portion 13 by means of cement. This cap 15 is formed as a shell having at its bottom an inturned flange 16 adapted to prevent outward movement of the cap when the 35 cement has set. The upper petticoat has, as is usual, a circumferential groove 17 defining a circumferential shoulder forming a head 13, which prevents the body of cement from slipping off after hardening.

To apply the cap it is merely necessary to fill the interior thereof with cement, force 40 it down upon the head 13, adjust the relative positions of the insulator and the cap until the latter has assumed its final position and allow the cement to harden.

In practice I prefer to place between the upper surface of the head 13 and the cap 15 a filler or spacer 19.

45 The purpose of the cap is to provide means for attaching a structure to the insulator. While the cap may assume various forms within the scope of its purpose I have

found that the form illustrated is particularly advantageous both in point of simplicity of manufacture and in point of operation.

As best shown in Fig. 2, the cap may have a plurality, for instance four depressions 20 affording space for the head of a bolt. 50 Above the upper surface of the shell is disposed a plate 21 having a plurality e. g. four radial slots 22 in registration with the depressions 20. While this plate 21 may be secured to the shell in any suitable way, 55 I prefer to spotweld it, as indicated by the points of welding contact 23.

The parts when permanently connected in this manner form a one-piece cap having a shell-like body, a top wall having grooves 60 for receiving a bolt head and flanges with bolt-receiving slots in vertical alignment with the grooves or depressions in the wall.

To attach a structure to the insulator, it is thus merely necessary to place bolts in the 65 depressions 20 and the radial slots 22 and into and through bolt holes on the structure to be attached. While I have shown four depressions and radial slots, two or three may be sufficient.

70 It is understood that various changes may be made in the arrangement shown. While the depressions and the plate 21 are disposed in a plane at right angle to the pin 11, they may be disposed at any desired 75 angle relatively thereto, according to the particular purpose.

I claim:—

1. A metallic insulator cap comprising a shell adapted to fit over the upper end of an 80 insulator and to receive cement for securing the said shell to the insulator, a wall closing the top of said shell, the said wall having a plurality of grooves therein of a width to receive a bolt head and flanges overlying 85 the respective grooves and having bolt-receiving slots opening into the same.

2. A metallic insulator cap comprising a one-piece shell adapted to be cemented to the top of an insulator, a wall closing the 90 top of said shell, the said wall having radial 95

- grooves therein which extend to the periphery of said shell, and flanges overlying the respective grooves and having bolt-receiving slots communicating with the same.
- 5 3. An attachment for insulators consisting of a metallic cap having a plurality of depressions in its outer surface and a

plate secured to the cap, having radial slots in registration with the depressions and defining therewith anchoring points for bolt heads.

In testimony whereof, I affix my signature.

BENJAMIN W. KERR.
